TELEPHONE TRANSMITTER

Harold C. Pye, Oak Park, Ill., assignor to Associated Electric Laboratories, Inc., Chicago, Ill., a corporation of Delaware

Application September 16, 1935, Serial No. 40,738

19 Claims. (Cl. 179—122)

This invention relates in general to telephone transmitters but more particularly to transmitters of the type employing carbon granulated material in the microphone cell and the broad object of the invention is to provide a transmitting unit particularly adapted for use in the handset type of instrument employed with the cradle type of telephone.

The principal object of the invention is to design a transmitter unit that will operate to transmit speech in a highly satisfactory manner regardless of the position in which the unit is held by the handset when in use.

Before proceeding with a detailed description of the invention it may be well to generally review the general characteristics of previous types of transmitter units and their particular defects or failings which is the general object of the transmitter concerned in the invention to overcome.

Since the initial introduction of the handset type of telephone unit, (transmitter and receiver mounted as a unit connected by a handle), particularly close contact has been maintained by engineers and others to note the performance of these units by tests and various observations and of those which have been in service for different lengths of time under numerous conditions of use. These tests and observations have made evident the desirable properties of an ideal handset transmitter, and in addition have pointed out the faults and weak points of the existing ones. In addition to testing and observing handsets in actual service here has been devised methods and means simulating the actual conditions of service by means of testing machines. These testing machines are essential in order to give accelerated ageing tests, position performance tests, transmitter response measurements, and many other tests that are necessary to accurately rate the performance of many proposed designs, in a reasonable length of time.

In order to make the problem and therefore the general object of the invention clear it may be well to set down the desirable properties of an ideal handset transmitter:

(a) A transmitter design which will serve for all service conditions.

(b) A transmitter which is sensitive enough to give adequate transmission volume on long telephone lines and also be able to carry the heavy current supply on short length of lines without developing carbon noise.

(c) A handset transmitter which can replace any fixed stationary transmitter type of tele-

phone without any deterioration of performance.

(d) A handset transmitter whose resistance is low enough to operate the central office signalling apparatus satisfactorily on all types of switching equipment. The resistance of the unit must meet with the foregoing requirement regardless of the position of the transmitter in which it is held, atmospheric conditions, or the length of time in which it has been in service.

(e) A transmitter unit in which the fidelity of response is as good as the present state of the art of electro-acoustical design will permit, without sacrifice of transmitting volume efficiency.

(f) A transmitter unit in which the response is independent of the position in which it is held while in use.

(g) A transmitter in which the volume efficiency or sensitivity does not change either gradually or periodically while in actual service.

(h) A unit which is independent of atmospheric conditions such as humidity, temperature, and pressure. Moisture from the breath condensing on the transmitter parts should not affect them.

(i) A transmitter unit which is able to give several years of normal telephone service without becoming noticeably noisy or declining in transmitting efficiency.

It will be obvious that some of the foregoing desirable properties in a handset transmitter are antagonistic to each other. A transmitter, as is well known, depends for its performance upon the movement of the diaphragm causing a resistance change in the microphone cell proportional to the movement. A given movement of the diaphragm will cause a certain percent change of the microphone resistance. It is therefore obvious that the higher the microphone cell resistance, the greater will be the resistance change and in a common battery line circuit the more sensitive will be the transmitter. Contrary to this, however, the higher the transmitter resistance, the higher will be the voltage across the microphone cell. The heat generated at the points of contact of the carbon granules in the cell is proportional to the square of the voltage between them. This heating causes thermal agitation of the granules and if great enough will be heard as a frying or sizzling noise in the receiver. In other words, the higher the transmitter resistance the greater the heat generated at the points of contacts of the carbon granules. The only known solution of this apparent dilemma is to so design the transmitter that the motion of the diaphragm causes a large percentage of change of resistance

and to make the resistance low enough to handle the greatest current supply encountered in practice without producing noise.

In the radio broadcasting art there have been developed transmitters with a high fidelity of response over a wide range of frequencies. The practice has been to use a very stiff but light diaphragm which is highly damped. This obviously gives a very insensitive transmitter, but in radio practice this is no great disadvantage as amplifiers are readily available. These transmitters are from forty to sixty decibels below the ordinary telephone transmitter in volume efficiency and are therefore entirely unsuited for ordinary telephone purposes. The fidelity of transmitters can, however, be much improved by the proper balancing of the resonant frequency of the diaphragm, the acoustical chambers in front and in back of the diaphragm together with the proper amount of damping, without a sacrifice of volume efficiency.

There have been many designs proposed tending to reduce the variation of performance of the transmitter with different positions of the handset. These range all the way from mounting the transmitter at some advantageous angle in the handset, to various shaped electrodes and microphone cells. Placing the transmitter at some angle is only a compromise as there will be some position in which the performance is poor even if this is farther removed from the normal position. Electrodes have been formed as cones of various angles, hemispheres, cylinders, and many other geometrical forms, with the purpose of maintaining contact between the granules and the electrodes in all of the different positions. Other designs involve immersing the electrodes in the granules so that contact is maintained between them in all the different positions. This is the type most commonly used commercially in transmitters at the present time.

It may be of interest here to analyze the action taking place in a microphone cell with the purpose of showing what is necessary to obtain "all position" performance, that is, correct operation of a handset transmitter when placed in use at any desired angle. In the quiescent state the carbon granules exert a pressure between each other and the electrodes due to the force of gravity. The carbon granules at the bottom of the cell (that is, in a direction toward the earth) will be compressed greatest, while those at the top of the cell least, and the pressure between the top and bottom will be some intermediate amount. The first requirement for "all position" performance is that the cell be so shaped that this quiescent compression be the same regardless of its position, for the resistance of the cell depends upon the compression of the granules. This could be quite simply accomplished by means of some approximately spherical form for the cell with the electrodes in the center if it were not for the fact that the granular carbon does not behave like a fluid. In a fluid the pressure in all directions at a given point is the same. Because of the friction between the carbon granules the pressure in a horizontal direction is much less than in the vertical direction. If two oppositely disposed plane parallel electrodes are placed in the center of a spherical cell of granules the resistance of the cell will be much greater when the electrode surfaces are horizontal than when they are in vertical position, even if the cell diameter is large with respect to the electrodes diameter. This is

so because the pressure is not transmitted horizontally between the electrodes as well as it is vertically. It is in this respect that the immersed electrode types of transmitter cells failed to fully accomplish their purpose.

The movement of the diaphragm under the action of sound waves compresses the granules more or less than they were compressed in the quiescent state, depending upon the direction of motion. This pressure as pointed out is not transmitted equally well in all directions through the granules, but is greater in the direction of motion, becoming less as the angle to this direction is increased until at right angles it is at a minimum. It is for this reason that many of the variously shaped electrodes are not successful. With the electrodes in the form of a cone the volume efficiency is less with a sharp cone than with a blunt one because less of the diaphragm movement is effective in compressing the granules. In the hemispherical or other curved surface electrodes the movement of the diaphragm is most effective in compressing the granules near the top of the hemisphere where the surface is most nearly at right angles to the direction of motion or compression of the granules. The sides of the hemisphere are almost parallel to the direction of motion and are therefore almost inactive. This inactive portion of the cell acts as an electrical shunt resistance on the active portion of the granules.

There has been considerable research made to find the ideal microphonic material. Many metals, minerals, and combinations of materials have been tried but it seems that carbon most nearly meets all of the conditions required. It is hard, has a low density compared to most metals, cannot be fused, does not corrode in air, can be made with a high degree of purity due to its inert nature, and above all, its microphonic properties are ideally suited for transmitters. Processes have been developed to manufacture both granular and electrode carbon with uniform properties at a reasonable cost. It is therefore possible to take advantage of its high microphonic efficiency for both granules and electrode materials. The use of metal electrodes in a transmitter cell either solid or plated with various alloys loses part of the microphone advantage of carbon at the electrode surfaces and depends entirely upon the microphonic action between the granules. Metal surfaces are quite likely to be soft and easily abraded by movement of the carbon granules.

With the foregoing objects in mind a transmitter unit has been designed according to this invention which most nearly meets all the conditions of an ideal handset transmitter as above enumerated and without employing expensive materials or construction methods in its quantity manufacture.

A preferred embodiment of the novel transmitter unit according to the invention is illustrated in the accompanying two sheets of drawings in which Fig. 1 shows a side cross-sectional view through the center of the transmitter unit; Fig. 2 is a rear view of the transmitter; Fig. 3 is an exploded perspective view of the elements comprising the microphone cell and the diaphragm; Figs. 4, 4A, 4B, 4C and 4D illustrate various shaped electrodes that may be used; Figs. 5 to 9 illustrate a number of graphs diagrammatically indicating performance characteristics of the transmitter unit made according to the invention.

Referring now more particularly to Fig. 1 of

the drawings, the external housing of the transmitter unit, indicated by the reference character 1, is constructed preferably of some aluminum alloy in order to obtain a rigid light-weight 5 mounting for the sensitive diaphragm assembly. The form is such that it can be used interchangeably with either the handset type of transmitter unit or the rigid desk stand type. The various shaped mouthpieces and supports which may be 10 used with the unit are not illustrated here. The housing 1 is cup-shaped and is arranged to support the various members and parts of the complete transmitter unit. An aluminum face plate 2 having a number of openings 3 arranged in a 15 circular pattern for the purpose of permitting the speech waves to reach the diaphragm, is placed in the flange 6 of housing 1. A thin edge 4 around the flange 6 is then spun over on the edge of face plate 2 to hold it firmly in place in the 20 housing 1. The groove 5 cut in the periphery of face plate 2 enables a sort of springing action to be applied to plate 2 when the edge 4 is pressed down and spun over on the face plate and a 25 tighter fit to be brought about.

26 The moving system comprising the diaphragm is made of extremely light material such as thin duralumin sheet metal. This metal combines the properties of light weight together with high tensile strength. Three separate parts are assembled 30 together to form the diaphragm system. The front part or main diaphragm 7 is conical in shape and has a relatively wide flange around its outer edge. A thin cushioning ring 8 of insulating material and a moisture proof protective 35 covering 9 completely covering the front of the diaphragm 7 are clamped by the face plate 2 directly on the flange of diaphragm 7 to the inside of the housing 1. Behind the main diaphragm 7 lies a secondary diaphragm 10 in the 40 shape of a conical ring having an opening in the center thereof. The secondary diaphragm 10 has a dome shaped cup 11 inserted through its opening which is provided with a flanged portion 14 resting against the edge of the opening. The 45 complete assembly comprising the diaphragm 7, secondary diaphragm 10, and the dome shaped cup 11 are then drawn together under tension to the position indicated in Fig. 1 and secured between the top of the dome 11 and the center of 50 the main diaphragm 7 by means of the eyelet or rivet 12, thus forming a diaphragm assembly which is very stiff over the center conical portion and extremely flexible around the outer edge flange of the diaphragm 7, the outer edge of the 55 diaphragm 7 being securely clamped as has been pointed out. The eyelet 12 has an opening 13, the purpose of which will be later on described. By utilizing the eyelet and rivet 12 to hold the assembly together in the center of the diaphragm 60 7 it is not necessary to provide additional means for rigidly securing the secondary diaphragm 10 at its periphery to the main diaphragm 7, or at the inner edge of the opening of this secondary diaphragm to the flange 14 of cup 11. This construction insures that the diaphragm moves as a 65 whole similar to a piston and will not vibrate in sections as a flat plate does when driven by sound waves of various frequencies. The foregoing assembly is in the nature of a "truss" diaphragm.

70 A ring shaped electrode 15 constructed of solid carbon is fastened to the flange 14 of the dome shaped cup 11 by turning up or spinning over the edge of the flange 14 on the electrode, thereby securely holding the electrode in its set position. 75 The moving electrode 15 is thereby rigidly fas-

tened to the diaphragm system and moves with it as a unit. Opposite the moving electrode 15 is a fixed ring shaped carbon electrode 16 of the same shape as the moving electrode 15. This is mounted in the spun over edge of the flange 19 5 of another dome shaped cup 18 which cup is rigidly fastened to the transmitter housing 1 by means of the nut or threaded ring 23. The cup 18 is electrically insulated from the housing 1 by means of the ring shaped insulating washer 21 10 and the insulating cylindrical ring 20 on the shank of the dome shaped cup 18. Between the outer edges of the carbon ring electrodes 15 and 16 there is cemented a flexible paper bellows 17 15 of circular shape as will be seen more clearly in Fig. 3. This paper bellows 17 confines the granular carbon in the cell which is formed between the two cups 11 and 18 and the electrodes 15 and 16. This bellows may be attached by means of a coating of varnish or other adhesive to the edges 20 of the electrodes. As a further function of the paper bellows 17 it provides a means so that as the moving system of the diaphragm is vibrated air is forced through the folds of the paper bellows 17 between the outside of the microphone 25 cell and the chamber in back of the diaphragm, thus slightly damping or controlling the vibrations of the diaphragm. The resonance chamber in front of the diaphragm 7 and moisture 30 proof covering 9 and behind the face plate 2 provides a further damping means for the moving system. The inner surfaces of the dome shaped cups 11 and 18 in contact with the carbon granules are covered with a suitable insulating enamel as indicated in Fig. 3 at 31 and 32 so that the current 35 flow in the microphone cell is confined to the carbon electrodes 15 and 16. For the purpose of illustrating the individual parts of the microphone cell more clearly the carbon granular material which almost completely fills up the space between the electrodes and the dome shaped cups 40 11 and 18, has not been shown in the drawings.

At the rear end of the dome shaped member 18 there is provided an opening whereby the microphone cell may be filled with the carbon granule 45 material. After the filling is completed the plug 30 is threaded into the opening and then the head of the plug is sheared or twisted off, precluding the possibility thereafter of unauthorized tampering with the parts comprising the microphone 50 cell.

The clamping ring 23 in addition to holding the dome shaped member 18 insulatingly clamped to the housing 1 directly clamps the terminal member 27 to it. At one end the terminal member 55 is fastened to the housing 1 by means of screw 28 and it has the terminal screw 28 inserted into it for the attachment of outgoing conductors. The terminal member 27 establishes electrical contact from the wires on terminal 28 with the front diaphragm 7 and electrode 15. The other terminal member 24 placed on top of but insulated for terminal member 27 by insulating washer 22 and insulator 20 establishes electrical contact 60 through the clamping ring 23 with the rear electrode 16. It has the holding screw 25 threaded into the housing 1 which is insulated therefrom by means of the insulating washers 26. Screw 25 serves as the attaching means for the outgoing wire. The electrical circuits for the microphone 70 cell extend from the attaching wire on screw 25, the terminal member 24, clamping nut 23, dome shaped member 18, the electrode 16 which is held in the flange 19 of the member 18, through the carbon granular material filling the cell to the 75

other electrode 15. Then the current passes out through the flange 14 and the dome shaped member 11, diaphragm 7 or secondary diaphragm 10, to the periphery of diaphragm 7, the housing 1 5 which is in contact with the edge of this diaphragm, through terminal member 27 in contact with the rear of the housing 1, to screw 28 and the outgoing wire. All of the current flowing through the transmitter unit takes place over the 10 foregoing electrical path.

The microphone cell is purposely constructed in the form described and illustrated so that pressure due to the force of gravity on the granules at the electrode surfaces is very nearly equal for 15 any position in which the cell is placed when in use. For the reason that the pressure is not transmitted as well in a horizontal direction between flat surfaces, the electrodes 15 and 16 have been formed as narrow rings, and the horizontal 20 direction of pressure flow is thus made very short. To assist further in the transmission of pressure between the electrodes the inner edge of them has been beveled at a small angle. In Fig. 4 25 various shaped electrodes with rounded edges and beveling angles are indicated which may be equally as well used for this purpose. The movement of the diaphragm 7 under the action of sound waves impinging on the front of it compresses the carbon granules between the electrodes and also compresses the mass of granules in the cell thereby varying the resistance of the 30 electrical current flow therethrough to electrically transmit the speech waves.

The common trend of development of telephone 35 transmission apparatus appears to be at the present time toward a more faithful reproduction of the voice. A measure of this fidelity is the response of a transmitter with frequency variations. The range of frequencies usually transmitted over 40 telephone circuits extend from 300 to 3500 cycles. The higher frequencies are necessary to make the voice clear and natural. An ideal transmitter would transmit all frequencies equally well. An indication of the improvements that have been 45 made toward this direction may be had by considering that the old desk transmitters responded hardly at all above 2000 cycles and that the total variation of response between 300 and 2500 cycles was 40 decibels or more. Previous types of handset transmitters, however, responded very well up 50 to 3500 cycles but the variation with frequency was too large, there being 30 decibels between 300 and 3500 cycles. Referring to the graph of Fig. 7 it will be noted that the improvement in the 55 transmitter according to the invention is quite considerable. It responds up to about 4500 cycles frequency and has a total variation in the response of only about 12.5 decibels up to that frequency, thereby providing an increased range of 60 operation and considerable better performance.

To measure the effect of changing the position of a handset upon the transmitting efficiency requires some means of maintaining all other conditions constant while the position is changed. 65 The well known artificial mouth equipment with the transmitter in fixed relationship to the mouth and so mounted that it can be moved to any angular position, is well adapted to this purpose. This artificial mouth equipment is described in 70 the Bell System Technical Journal, vol. 2, No. 2, page 293. The action of the transmitter according to the invention when subjected to tests with the machine is graphically illustrated in Fig. 5 75 in which the various positions of the handset are indicated at the different angles from the vertical

position. It will be seen from this graph that the transmitter has a total variation of only 1.7 decibels throughout a range of different positions while former types of handset transmitters have shown a total variation of as much as 10 or 5 more decibels for the different positions.

Under the same tests the resistance of the transmitter microphone cell was measured with the handset position changed to various angles as indicated in Fig. 6. As shown on this graph 10 the resistance limits for the transmitter are 29 to 37 ohms indicating a very small change of resistance compared with previous types of transmitters which vary from 30 to 90 ohms with 15 changes of position.

It is well known that "breathing" is a periodical variation of transmitter resistance due to the expansion of air in the microphone cell and of the cell walls by the action of heat which is generated by the passage of current through the cell. 20 Nearly all transmitters in use are of the sealed cell type which develop "breathing" if left in the circuit for several minutes. This disadvantage has been eliminated in the transmitter according to the invention by providing a small air vent 25 13 in the eyelet 12, Figs. 1 and 3, extending from the interior of the cell to the space between the diaphragm 7 and the protective covering 9. The opening 13 is small enough so as to prevent escape 30 of the carbon granules while permitting the heated air to pass through to the space. The cup shaped form of the cell walls of members 11 and 18 are such that the heating of them causes a slight expansion in a direction so as to lower the 35 resistance of the carbon granules rather than to raise it as is usual in older designs. The results of these improvements are evident on the graph indicated in Fig. 8 of the transmitter resistance plotted over a period of several minutes. The older types of transmitter units when in use indicate definite increase in resistance at periodic 40 intervals over a period of time, while the transmitter according to the invention indicates no such action whatsoever.

It is well known that packing of the carbon 45 granules in a microphone cell will effect a reduction of the resistance of a microphone cell due to the granules assuming a configuration that results in abnormal pressures between them in the quiescent state. As is clearly seen in Fig. 1 approximately half of the carbon granules of the 50 microphone cell are carried directly in the moving system comprising diaphragm 7, electrode 15, and the cup 11. It is therefore seen that any movement of the diaphragm 7 moves these granules thus breaking up any packed condition and 55 restoring the transmitter to its normal sensitive condition.

The so-called "carbon noise" is the chief limitation to current carrying capacity of a transmitter. As is well known a handset transmitter will receive rather rough treatment in service, such as dropping on the cradle or on a table, moving about while in use, and placing in a horizontal position on the cradle just before being used. 65 This all tends to make the transmitter become noisy when in use. To reduce these effects to a minimum the transmitter according to the invention was designed to have a lower resistance in all positions than previous types did. In order 70 to test the new transmitter an artificial ageing cycle was performed by a machine that simulated the condition of removing the transmitter from the cradle and raising it to the talking position and then dropping it on the cradle, the current 75

supply being turned on and off as it would be by the cradle switch. The operation of dropping the handset on the cradle does the most damage. This artificial ageing machine gives a more severe shock in this respect because the transmitter is dropped directly upon a non-resilient anvil. The cradle switch and the handset mounting reduce the shock in actual practice. As indicated in the graph of Fig. 9, 20,000 of the foregoing artificially ageing operations of the transmitter of the invention have been made. The graph indicates both the resistance of the carbon granules and the carbon noise level taken with a battery feed current of approximately 0.250 ampere. From these curves it is seen that the resistance and noise level of the transmitter reaches a fairly constant value after about 10,000 operations. The resistance and noise are less after 20,000 operations of the transmitter of the invention than older types of handset transmitters were at approximately only 1,000 operations. 20,000 ageing operations would be practically the equivalent of ten years of service with about five operations a day. This graph indicates that the ageing of the transmitter carbon granules due to shock has been eliminated to a large extent by the new design.

The use of the anti-side-tone telephone substation circuit effectively prevents howling or excessive side tone when a handset is connected to the line. When a telephone is used on a short line loop and before the called party answers the line circuit is virtually open. Under these conditions any side tone circuit is not balanced and in some cases the handset may tend to sing or howl. Although this does not usually take place during conversation it is nevertheless annoying. With the transmitter of the invention as indicated in the graph of Fig. 7 the relatively flat response frequency curve of the transmitter greatly reduces this tendency to howl and sing. The very light moving system of the transmitter likewise reduces the mechanical coupling between it and the receiver in the handset. This transmitter can therefore be used on any type of circuit, side tone or anti-side tone without self-oscillations impairing its satisfactory performance.

It is essential that the transmitters be sealed against moisture. The transmitter according to the invention is effectively sealed by providing a moisture proof protective diaphragm 9 over the main diaphragm 7 which seals the front aperture against moisture. All other joints such as the filling plug 30, the ring-nut 23, and the screws 28 35 are also sealed with water proof compound. The transmitter can therefore be immersed in water for a considerable length of time without any impairment in its performance.

The invention having been described what is considered to be new and is desired to be protected by Letters Patent will be set forth in the following claims.

What is claimed is:

- 65 1. In a transmitter, a cone-shaped diaphragm, a dome-shaped cup secured to the apex of said diaphragm, a conical ring clamped between the outer edge of said cup and said diaphragm, and an electrode secured to the outer edge of said cup.
- 70 2. In a transmitter, a diaphragm comprising two conical-shaped members having their peripheries in contact, a cup member having its bottom secured to the apex of one of said conical members and its edges in contact with the other of said

members, and an electrode secured to the edge of said cup member.

3. In a telephone transmitter, a microphone cell including two cup-shaped members oppositely disposed, an electrode mounted on the edge of each of said cup members, a flexible member connecting said electrodes together and enclosing said microphone cell, and a diaphragm attached to the base of one of said cup members.

4. In a telephone transmitter, a pair of oppositely disposed dome-shaped members forming a microphone cell, a flange around the edges of each of said members and an electrode supported by the flange on each of said members.

5. In a telephone transmitter, a diaphragm 15 comprising a pair of oppositely disposed conical shaped members, a dome-shaped cup member clamped at its bottom to one of said conical members and in engagement with the other of said conical members at the periphery of the 20 cup, a housing for said diaphragm, means in said housing for clamping said diaphragm at its periphery, said diaphragm being flexible near its clamping periphery while remaining entirely rigid from a point near the periphery to its center 25 and including said cup member.

6. In a transmitter, a conical diaphragm, a cup member, an eyelet for securing said cup member to said diaphragm and having an opening therein, a second cup member disposed oppositely to said first cup member, electrodes secured to the edges of each of said cup members, a flexible member extending between the faces of said electrodes, said cup members, electrodes, and flexible member completing the confines of the 35 microphone cell of said transmitter, a plugged opening in the bottom of said second cup member, carbon granular material filling said microphone cell and inserted through the opening of said second cup member, the opening in said eyelet 40 being of a size to preclude the escape of the carbon granular material from said cell but permitting the escape of gases from said cell generated due to the passage of current between said electrodes.

7. In a telephone transmitter, a cylindrical shaped microphone cell having hemi-spherical ends, a pair of electrodes located in said cell, a diaphragm secured to one end of said cell, granulated carbon material filling said cell, and means 50 for preventing the escape of the carbon granules from said cell while at the same time permitting the escape of gases generated by the passage of current through said granules between said electrodes.

8. In a transmitter, a diaphragm comprising two conical members having their peripheries abutting, a microphone cell having one end attached to the apex of one of said conical members and the other end to an opening in the other 60 conical member, and an electrode fastened to said microphone cell adjacent the opening in said other conical member.

9. A transmitter diaphragm comprising a pair of conical members with their peripheries in 65 abutment and their apexes extending in opposite directions and a portion of a microphone cell formed between said apexes.

10. A transmitter diaphragm comprising a pair of conical members having their peripheries in 70 abutting relationship and their concave surfaces extending away from one another to form a hollow space between said members, and a portion of a microphone cell disposed in said space.

11. In a telephone transmitter, a diaphragm 75

- comprising a pair of conical-shaped members having their peripheries in abutment and their concave surfaces extending away from each other, a portion of a microphone cell extending 5 through an opening in the center of one of said conical members and attached to the apex of the other conical member, the apex of said other conical member and said microphone cell having an opening therein at their place of attachment, 10 and an electrode secured to said microphone cell around the opening in said first conical member.
12. In a telephone transmitter, a pair of hemi-spherical shaped members having their open edges spaced opposite one another forming a 15 microphone cell, resistance material in said cell, means for insulating the walls of said cell from said resistance material, an electrode supported on the edges of each of said hemi-spherical members, flexible means extending between said electrodes, a diaphragm supporting one of said hemi-spherical members at its base, and a rigid support 20 for the other of said members.
13. In a telephone transmitter, a pair of hemi-spherical shaped members arranged with their 25 open edges spaced opposite one another and defining a microphone cell, a circular electrode supported on the edge of each of said members, resistance material in said cell, and means insulating the cell walls of said members to confine the current flow through said resistance 30 material and between said electrodes.
14. In a telephone transmitter, a microphone cell comprising a pair of cup-shaped members having their open edges facing each other and 35 the bottoms of the cups extending in opposite directions, a ring-shaped electrode supported around the edge of each of said cup members, insulating material on the cell walls of said cup members for confining the current flow between 40 said electrodes, means for rigidly supporting one of said cup members, and a diaphragm for movably supporting the other cup member.
15. In a telephone transmitter, a microphone 45 cell, a pair of electrodes in said cell, a diaphragm supporting one of said electrodes and movable therewith, means for rigidly supporting the other electrode, resistance material in said cell, means for confining the current flow through said cell between the electrodes and the resistance ma- 50
- terial, one end of said cell and said diaphragm having an opening therein for equalization of air pressure between the inside and outside of said microphone cell.
16. In a telephone transmitter, a microphone 5 cell filled with resistance material, a diaphragm attached to one end of said cell, said cell and said diaphragm having openings in alignment 10 therein extending from the inside to the outside of the cell to maintain the air pressure constant 15 within the cell when in use, said opening being of a size to prevent the escape of the resistance material from said cell.
17. In a microphone cell containing resistance 20 material and a diaphragm attached to one end of the cell, the provision of means for permitting the equalization of air pressure between the inside and the outside of the cell and diaphragm while preventing the escape of the resistance material therefrom.
18. In a telephone transmitter, a microphone 25 cell, a diaphragm, a movable and a rigid electrode spaced apart in said cell, said movable electrode attached to said diaphragm and movable therewith under the action of sound waves 30 impinging against said diaphragm, resistance material in said cell, an air passage extending from the inside of said cell to the side of the diaphragm receiving the sound waves, said air passage enabling the equalization of air pressure 35 between the inside of the cell and the outside of said diaphragm to prevent the undesired movement of the movable electrode caused by the cell expansion.
19. In a telephone transmitter, a casing, a 40 conical diaphragm, a conical protective disc, a face plate having a conical surface, said protective disc arranged between said diaphragm and said face plate so that the conical surfaces of each element are in nested formation, said conical elements having extended flat surfaces parallel to each other forming their clamping peripheries, said face plate securely clamping said protective disc and said diaphragm to said casing 45 at said peripheries in such a manner that a narrow space is provided around their adjacent conical surfaces.

HAROLD C. PYE.
